UNITED STATES PATENT OFFICE.

PETER MURRAY, JR., OF NEWARK, NEW JERSEY, ASSIGNOR TO THE MURRAY MOTOR MANUFACTURING COMPANY, OF SAME PLACE.

GAS-ENGINE.

SPECIFICATION forming part of Letters Patent No. 351,393, dated October 26, 1886.

Application filed June 6, 1883. Serial No. 97,248. (No model.)

To all whom it may concern:

Be it known that I, PETER MURRAY, Jr., a citizen of the United States, residing at Newark, county of Essex, and State of New Jersey, have invented certain new and useful Improvements in Gas-Engines, fully described and represented in the following specification and the accompanying drawings, forming a part of the same.

10 This invention relates, generally, to that class of gas-engines in which the power is obtained by the explosion of a mixture of gas and air in the cylinder of the engine, but more particularly to that class of these engines in which 15 the explosive mixture is confined in the cylinder under a considerable pressure previous to being exploded.

20 To aid in a more ready understanding of the invention, and of the details in the construction and organization of the engine, to be hereinafter described, a brief description of the general organization and operation of the engine will be first given.

25 The air and gas which form the explosive mixture are first admitted in suitable proportions into a chamber containing a mixing apparatus. This chamber is connected by a supply-pipe with one end of each of a pair of double-acting pumps, which operate to draw 30 the air and gas through the mixing apparatus, and thus form these fluids into a homogeneous mixture. These pumps are arranged to operate alternately—that is to say, one pump is arranged to draw in a charge of the explosive 35 mixture while the other pump is forcing out the charge drawn in at the last stroke, and are connected by suitable induction-pipes with the opposite ends of the power-cylinder, so that the charges of the explosive mixture are forced

40 into the opposite ends of the power-cylinder alternately. The piston of the power-cylinder and the pistons of the pumps are so timed with relation to each other that the charges are forced into the power-cylinder while the piston is upon its stroke toward the end of the cylinder into which the charge is being forced, from which it results that the charges are compressed to a considerable extent before being exploded. The induction-pipes leading from 45 the pumps to the opposite ends of the power-cylinder are provided with suitable induction-

valves, by which the charges are confined in the power-cylinder. The exploding of the charges in the power-cylinder is effected by means of a pair of firing-valves, which are operated from an eccentric upon the main crank-shaft, so that at the proper times communication is opened between the charges confined in the power-cylinder and igniting-burners, which are located in the sides of the valve-chests. The igniting-burners are fed through suitable ducts from the charges in the power-cylinder, and are relighted after each charge is exploded by master-lights, which are located at the sides of the valve-chests. The power-cylinder is provided with two exhaust-openings, located near its opposite ends and in such position as to be uncovered when the power-piston is at the ends of its strokes. These openings are controlled by exhaust-valves, which 70 are positively opened as the piston arrives at the end of its stroke, to permit the products of combustion to be exhausted from the cylinder, and are connected by suitable exhaust-pipes with the other ends of the pumps which force 75 the charges into the power-cylinder. The pistons of these pumps, as before stated, are so timed with relation to the power-piston that they operate to compress the charges into the power-cylinder. From this it results that partial vacuums are formed in the pumps before the exhaust-valves are opened, so that as soon as the valves are opened the products of combustion in the power-cylinder are drawn rapidly out into the pumps, from which they are 80 forced through an escape-pipe to the open air.

85 The invention consists, principally, in the means for compressing the charges of the explosive mixture into the power-cylinder and for exhausting the products of combustion after the charges have been exploded, and in the means for effecting the explosions at the proper times.

90 The invention also embodies the various details of construction in other parts of the engine, all of which will be hereinafter fully explained and particularly pointed out.

95 The details in the construction of the organization hereinbefore briefly outlined will now be described, reference being had to the accompanying drawings, in which—

100 Figure 1 is a side elevation of a gas-engine

embodying the present invention. Fig. 2 is an irregular horizontal section of the same, showing particularly the pump and power pistons, the firing-valves, and the igniting-burners, the parts being shown in the same position as in Fig. 1, which is the position they will occupy just after a charge has been exploded in the outer end of the power-cylinder and the power-piston has commenced its inward stroke. Fig. 3 is an irregular vertical cross-section upon an enlarged scale, taken on the line *x x* of Fig. 2. Fig. 4 is a similar view taken upon the line *y y* of the same figure. Fig. 5 is a longitudinal vertical section of the pumps upon a like scale, taken upon the line *z z* of Figs. 2, 3, and 4. Fig. 6 is a sectional detail upon a like scale, taken upon the line *w w* of the same figures. Fig. 7 is a vertical section, upon a like scale, of the mixing apparatus, taken upon the line *v v* of Figs. 2 and 5, and Fig. 7^a is a detail of the same. Fig. 8 is an enlarged horizontal section of the firing-valves and valve-chests and the igniting-burners, taken on the line *x x* of Fig. 10. Fig. 9 is a longitudinal vertical section, upon the same scale, of the slide-plates of the valve-chests, showing the ports and ducts therein. Fig. 10 is a cross-section taken on the line *x x* of Fig. 8. Fig. 11 is a similar view taken on the line *y y* of the same figure. Fig. 12 is a similar view taken on the line *z z* of the same figure. Fig. 13 is a similar view taken on the line *w w* of the same figure. Fig. 14 is an outside face view of one of the firing-valves. Fig. 15 is a horizontal section of the same, taken on the line *x x* of Fig. 14; and Fig. 16 is a horizontal section of the power-cylinder, illustrating a modified arrangement of the exhaust-ports, which will be hereinafter explained.

Referring to said drawings, it is to be understood that the power-cylinder 150 is arranged in a horizontal position upon a suitable frame-work, A, which at a proper distance in front of the cylinder is provided with bearings for the main crank-shaft 149. The power-piston 148 is provided with the usual piston-rod, 147, which passes through a suitable stuffing-box in the end of the cylinder, and is connected to the main crank 146 by means of a pitman, 145. The piston-rod and pitman are provided at their point of connection with the usual cross-head, 144, which moves back and forth upon a suitable bearing, 143, formed on the frame-work.

In the organization here shown the charges of the explosive mixture, instead of being drawn into the opposite ends of the power-cylinder by the piston 148, are forced into each end of the cylinder after the piston has completed its stroke toward the opposite end of the cylinder and while it is upon its return-stroke, thereby allowing the charges to be compressed to a considerable extent in the power-cylinder. The supplying of the charges to the power-cylinder is effected by means of two double-acting force-pumps, 141 142, which are located by the side of the cylinder and

have their pistons 139 140 secured to a single rod, 138, which is connected by a pitman, 137, with a second crank, 136, upon the main shaft 149, the point of connection between the rod 138 and the pitman being provided with the usual cross-head, 135, which slides in a bearing, 134, upon the frame-work. The cranks 136 146 are so positioned that the power-piston completes its stroke just in advance of the pistons of the pumps. The purpose of this arrangement will appear when the operation of the engine is explained.

In order to effect the rapid and complete combustion of the explosive mixture in the power-cylinder, which must be accomplished in order to obtain the best results, it is necessary that the air and gas which enter into the explosive mixture should be thoroughly commingled before they enter the cylinder. This is effected by means of a mixing apparatus through which the air and gas are drawn as they enter the supply-pipe 98, through which the mixture is drawn into the pumps. This mixing apparatus is located in a chamber, 99, (see Fig. 7,) into which the gas and air are first admitted—the former through a pipe, 97, leading from the source of supply, and the latter through an opening, 96, formed in the bottom of the chamber, and controlled by an ordinary check-valve, 95. The pipe 97 communicates with an annular chamber, 94, which forms a seat for a check-valve, 93, and is provided with a number of openings, 2, (see Fig. 7^a,) which are covered by the flange of the valve. By this means the gas which enters into the explosive mixture is distributed in a large number of small streams around the air, which is admitted through the opening 96 and the central opening of the chamber 94, and thus the mixture of the two fluids is partially effected. The valve 93 also affords means by which the escape of any of the mixture from the chamber 99 is prevented when the engine is not in use. The pipe 97 and the opening 96 will preferably be provided with suitable cocks or valves, (not shown,) by which the proportions of air and gas which enter into the explosive mixture may be varied at pleasure to suit the different running conditions of the engine.

The mixing apparatus proper consists of one or more mixing-wheels, which are mounted to turn freely upon a shaft, 91. Each of these wheels is composed of a number of blades or vanes, 15, which are arranged obliquely to the shaft, like the blades of a propeller or the vanes of a windmill, so that as the gas and air are drawn through chamber 99 by the action of the pumps, the current thus formed will cause the blades 15 to revolve, thereby agitating the air and gas, and causing them to become thoroughly mixed. The blades 15 of the different wheels will preferably be inclined in opposite directions, as shown, so that the wheels will revolve in opposite directions, and thus more thoroughly agitate and mix the air and gas.

From the mixing apparatus the explosive

5 mixture enters the supply-pipe 98, which is closed at its ends by perforated plates 89, (see Fig. 5,) upon the outsides of which are arranged ordinary flap-valves, 90, which open 10 outward into chambers 88, which communicate through ports 50 with the outer ends of the pumps 141 142. The chambers 88 also communicate, by means of induction-pipes 55 56, with the induction-chambers 40 (see Figs. 10 2 and 3,) at the opposite ends of the power-cylinder. The openings of the induction-pipes 55 56 into the induction-chambers 40 are controlled by the induction-valves 41, which close 15 as soon as the pressure in the power-cylinder exceeds that in the induction-pipes, and thereby confine the charges in the power-cylinder. The induction-pipes are also provided with the check-valves 42, (see Figs. 1, 3, and 4,) located near the chambers 88, by which the explosive mixture in the pipes is retained and prevented from being drawn back into the pumps upon their suction-strokes. From this arrangement it will be seen that the charge of explosive mixture drawn into each of the 20 pumps from the pipe 98 at one stroke is upon the next stroke forced out through the induction-pipe into the corresponding end of the power-cylinder. The cylinders of the pumps 141 142 are of such size with relation to the power-cylinder that the quantity of the explosive mixture which will be drawn into either of the pumps upon its suction-stroke and forced out of the pump into the power-cylinder upon the next stroke will be just sufficient 25 for one charge in the power-cylinder when the engine is running under ordinary working conditions. It will also be seen, by reason of the relative arrangement of the pump and power pistons, that the charges as they are forced 30 into the cylinder are, by the combined action of the two pistons, very greatly compressed, so as to be reduced to a comparatively small volume in the power-cylinder before they are fired. The induction-pipes 55 56 are connected 35 by a pipe, 54, (see Fig. 1,) which communicates with the two induction-pipes between the induction-valves and the valves 42. The purpose of this pipe will appear when the operation of the engine is explained.

40 The charges which are forced into the power-cylinder by the pumps, and confined therein by the induction-valves 41, are exploded at the proper times by means of stationary igniting-burners 20, (see Fig. 2,) which are brought 45 into communication with the charges by means of a pair of firing-valves, 30, which are located in valve-chests 31 at the opposite ends of the cylinder, which chests open into the induction-chambers 40. The firing-valves 30 are 50 connected to a valve-rod, 32, which passes through the valve-chests, and is operated by a rod, 86; from an eccentric, 85, upon the main crank-shaft. The eccentric 85 is so positioned upon the shaft that the valves 30 will be 55 brought into position to open communication between the burners 20 and the charges in the

cylinder just as the power-piston commences its return-stroke after completing the compression of the charge.

Referring now particularly to Figs. 8 to 15, 70 inclusive, the construction and arrangement of the devices for firing the charges will be described. The igniting-burners 20 are located in recesses 33 in the plates 51, which form the sides of the valve-chests, and consist of simple 75 pieces of sponge-iron or other similar substance, through which the gas can pass slowly. These burners are fed from the charges in the power-cylinder as follows: The plates 51, which form the sides of the valve-chests, are provided 80 with inwardly-extending flanges 21, which rest upon the bottoms of the valve-chests. These flanges 21 are provided upon their under sides with channels 3, (see Fig. 11,) which communicate with the induction-chambers 40 and with 85 vertical ducts 4, formed in the plates 51, which ducts communicate with horizontal ducts 5, (see Figs. 11 and 8,) which in turn open into the recesses 33 behind the burners 20. The plates 51 are provided with valves or plugs 34, 90 the ends of which enter the ducts 5, and by which the amount of the explosive mixture allowed to pass to the burners 20 can be regulated at pleasure. The igniting-burners 20 are re-lighted after each explosion by means of permanent master-lights 35, which are located outside the plates 51, just below the igniting-burners, and which are brought into communication (see Figs. 8, 9, and 13) with the igniting-burners at the proper times by means of ports 19, 95 formed in the plates 51, just above and below the recesses in which the igniting-burners are located, and channels 18, formed on the outer faces of the firing-valves.

In order to permit the igniting-burners 20 105 to be brought into communication with the induction-chambers 40 at the proper times to fire the charges, the firing-valves 30 are constructed as follows: The valves are provided with small explosion-chambers 22, having obliquely-arranged ports 9, (see Figs. 14 and 15,) which open outward through the outer faces of the valves in such position that as the valves are reciprocated they will be brought into communication with the recesses 33, (see Figs. 8, 115 9, 10,) in which the igniting-burners are located. The chambers 22 are also provided upon their upper sides with ports, which are closed by upwardly-opening check-valves 10, (see Figs. 10 and 12,) located in recesses 11, 120 which open inward into the induction-chambers 40. The inner faces of the side plates, 51, of the valve-chests are provided with vertical channels 8, (see Fig. 12,) which communicate with channels 7, formed in the bottoms of the flanges 21, and which open into the induction-chambers 40. The channels 8 are so positioned 125 that as the valves 30 are reciprocated the ports 9 will be brought into communication therewith, and, through the channels 7, into communication with the induction-chambers 40. The rod 32, to which the valves 30 are con-

ected, passes through two small cylinders, 36, located at the ends of the valve-chests, and is reduced in size in these cylinders, so as in effect to provide the cylinders with single-acting plungers. These cylinders communicate, by means of pipes 37, with pipes 38, which lead from a source of gas-supply and communicate with ducts, 6, (see Fig. 9,) formed in the plates 51, which ducts open upward and inward and 10 communicate with horizontal channels 1, (see Fig. 8,) formed in the inner faces of the plates, and in such position that as the valves 30 are reciprocated they are brought into communication with the ports 9. The pipes 38 are provided with ordinary suction and force valves, 16 17, located, respectively, upon opposite sides of the pipes 37. The purpose of this construction and arrangement will be made clear when the operation of the engine is described.

The power-cylinder is provided with two exhaust-openings, consisting of one or more ports, 43 44, which are located near the opposite ends of the cylinder, and in such position 25 as to be uncovered when the power-piston is at the ends of its strokes. These ports open into exhaust-chambers 46, (see Fig. 4,) which communicate, by means of exhaust-pipes 60 61, with ports 52, which open into the ends 30 of the pumps 141 142, opposite to the ports 50. The pipes 60 61 are connected by a pipe, 47, which is provided with an escape-pipe, 48, through which the exhaust products of combustion pass to the open air. The pipe 35 47 is provided with two ordinary check-valves, 39, (see Fig. 6,) which close upon the suction-strokes of the pumps. The communication between the exhaust-chambers 46 and the exhaust-pipes 60 61 is controlled by a pair of 40 upwardly-opening exhaust-valves, 28 29, the rods 27 of which pass upward through the tops of the chambers 46, (see Figs. 1 and 4,) and are provided at their upper ends with pivoted weighted arms 26, which are acted on alternately by a pivoted lever, 25, having an arm, 45 24, which is connected to the valve-rod 32. The purpose of this arrangement will also be made clear when the operation of the engine is described.

The power-cylinder is provided with the usual water-spaces, 23, through which water is caused to circulate to prevent the undue heating of the parts, and this cylinder is also provided at its end with a trough, 53, (see 50 Fig. 2,) through which the piston-rod passes, and which is also filled with water to keep the rod cooled and lubricated. The trough 53 is so deep that the piston-rod may be kept immersed, and is open at its top, so as to permit 55 easy access to be had to the stuffing-box in the cylinder-head to keep the packing properly adjusted. The trough is also provided with a stuffing-box, through which the rod passes. The trough 53 may be kept supplied with water from the outlet of the water-spaces 23, or 60 in any other suitable manner.

The walls of the cylinders 141 142 of the pumps are provided with chambers 49, into which petroleum or other hydrocarbon may be introduced, to be converted into gas by the heat given off from the products of combustion which are drawn from the power-cylinder into the pumps. By this means the heat which would otherwise go to waste may be utilized to produce gas for running the engine 75 or for other purposes. This feature is not, however, herein claimed, as it will form the subject-matter of a future application for Letters Patent.

The operation of the engine thus organized 80 is as follows: In describing this operation let it be assumed that the engine is in operation, and that the parts are in the position shown in Figs. 1, 2, and 8—that is to say, let it be assumed that a charge has just been fired in the outer end of the power-cylinder, and that the power-piston has just commenced its inward stroke. It will be observed that the eccentric 85 is so positioned with relation to the crank 146 that the firing-valves and the power-piston do not complete their strokes simultaneously, but that the latter completes its stroke slightly in advance of the former. From this it results that the power-piston commences its stroke in either direction slightly before the 95 firing-valves have completed their stroke in the opposite direction. At the same time, therefore, or slightly after the power-piston commences its inward stroke, as just assumed, the firing-valves will complete their outward 100 stroke. As the firing-valves arrive at the limit of their outward stroke, the end of the lever 25 will pass by the end of the pivoted lever 26 of the exhaust-valve 28, and thereby allow the valve to fall to its seat and close the 105 exhaust-pipe 60. At the same time that this takes place the opposite end of the lever 25 will pass by the end of the other lever, 26, thereby allowing the weighted end of the latter lever to fall, so as to bring the lever into 110 position to be engaged by the lever 25 upon the return-stroke of the firing-valves. As the firing-valves arrive at the end of their outward stroke, as just stated, the channel 18 of the valve at the inner end of the cylinder will be 115 brought into communication with the ports 19 and the recess 33, thereby establishing communication between the master-light and the igniting-burner at that end of the cylinder, as shown in Figs. 8 and 13, and at the same time 120 the port 9 of the same valve will be brought into communication with the channel 8, thereby establishing direct communication between the explosion-chamber 22 and the interior of the power-cylinder, as shown in Figs. 125 8, 9, and 12. Just after the power-piston has commenced its inward stroke, and at or about the same time that the exhaust-valve 28 is closed, as just stated, the pistons 139 140 of the pumps will commence their inward stroke, 130 thereby drawing a charge of the explosive mixture through the mixing apparatus and

the pipe 98 into the cylinder 141, and at the same time forcing the charge which was drawn into the cylinder 142 upon the last stroke out through the induction-pipe 56, and past the 5 valves 42 41, into the inner end of the power-cylinder, and also forming a partial vacuum in the cylinder 142 upon the opposite side of the piston 140. As the charge thus forced out of the cylinder 142 enters the power-cylinder 10 a portion of it will pass through the channels 78 and port 9, and fill or partially fill the explosion-chamber 22, and a portion of it will also pass through the channel 3 and ducts 4 5 to the recess 33, to feed the igniting-burner, 15 which burner will then be immediately lighted by the master-light 35. As the power and pump pistons proceed upon their inward strokes, the pump-piston will continue to force the charge out of the pump-cylinder into the power-cylinder until the power-piston arrives at the 20 end of its inward stroke, at which time, owing to the relative arrangement of the two pistons, the charge will be compressed to a comparatively small volume in the power-cylinder. 25 While the power and pump pistons are proceeding upon their inward strokes, as just stated, the firing-valves will also be moved in the same direction, and as this takes place the channel 18 will be carried out of communication 30 with the ports 19 and the recess 33, so that after the igniting-burner is lighted communication will be cut off between that burner and the master-light; but being fed from the charge in the power-cylinder the igniting-burner 35 will continue to burn in its recess 33. At the same time that this takes place the port 9 will pass out of communication with the channel 8, and will be brought into communication with the channel 1, thereby establishing communication 40 between the pump 36 and the explosion-chamber 22, and permitting a quantity of gas to be forced into the chamber by said pump, so as to increase the pressure of and also enrich the mixture in the chamber. As the firing-valves continue their inward movement, the port 9 will pass out of communication with the channel 1, and immediately after this takes place, and just as or slightly after the power-piston arrives at the end of its stroke, the port 45 50 55 60 65 70 75 80 85 90 95 100 105 110 115 120 125 130 135 140 145 150 155 160 165 170 175 180 185 190 195 200 205 210 215 220 225 230 235 of using one end of each pump for exhausting and the other end for charging the engine, one pump may do all of the exhausting and the other all of the charging. It is also to be understood that the engine may be arranged vertically instead of horizontally, and also that it may be made single instead of double acting, and yet preserve certain features of the invention. In the case of a single-acting engine two single-acting pumps will be employed, and one of the firing-valves will be omitted, and only one set of exhaust-ports will be provided.

What I claim is—

- 15 1. The combination, with the power-cylinder having an exhaust-opening located in position to be uncovered by the piston as it arrives at the end of its stroke, of an exhaust-valve which is opened at the end of the stroke, a pump by which a partial vacuum is formed in the exhaust-pipe before the valve is opened, and a pump by which a portion of a fresh charge is compressed in the induction-pipe before the exhaust-valve is opened, whereby 25 as soon as the exhaust-valve is opened, so as to reduce the pressure in the power-cylinder, the fresh charge will expand into the cylinder and drive the exhaust products before it out through the exhaust-opening, substantially as 30 described.
2. The combination, with the power-cylinder having the exhaust-openings located in position to be uncovered by the power-piston as it arrives at the ends of its strokes in opposite 35 directions, of exhaust-valves which are opened at the ends of the strokes, and a pump or pumps by which a partial vacuum is formed in the exhaust-pipes before the valves are opened, substantially as described.
- 40 3. The combination, with the power-cylinder having an exhaust-opening controlled by an exhaust-valve which is opened at the end of the stroke, of a pump by which a partial vacuum is formed in the exhaust-pipe before the valve is opened, and a pump by which the charges are forced into the power-cylinder in front of the advancing piston upon its return-stroke, substantially as described.
- 45 4. The combination, with the power-cylinder having an exhaust-opening located in position to be uncovered by the piston as it arrives at the end of its stroke, of an exhaust-valve which is opened at the end of the stroke, a pump by which a partial vacuum is formed in the exhaust-pipe before the valve is opened, and a pump by which the charges are forced into the power-cylinder in front of the advancing piston upon its return-stroke, substantially as described.
- 55 5. The combination, with the power-cylinder having the exhaust-openings located in position to be uncovered by the power-piston as it arrives at the ends of its strokes in opposite directions, of exhaust-valves which are opened at the ends of the strokes, a pump or pumps by which a partial vacuum is formed in the exhaust-pipes before the valves are opened,

and a pump or pumps by which the charges are forced into the power-cylinder in front of the advancing piston upon its return-stroke, substantially as described.

6. The combination, with the power-cylinder, of a double-acting pump, one end of which operates to form a partial vacuum for exhausting the products of combustion from the cylinder, while the other end operates to force the charges into the cylinder, substantially as described.

7. The combination, with the power-cylinder, of two double-acting pumps, one end of each pump operating to form partial vacuums for exhausting the products of combustion from the cylinder, while the other end of each pump operates to force the charges into the cylinder, substantially as described.

8. The combination, with the power-cylinder and a pump for compressing the charges into the cylinder, of an induction-pipe connecting the pump and cylinder and having the check-valves 41 42, whereby a portion of the charge is entrapped under pressure in the induction-pipe, and is permitted to expand into the cylinder to aid in expelling the products of the last explosion as soon as the exhaust is opened, substantially as described.

9. The combination, with the power-cylinder having an exhaust opening or openings, of an exhaust valve or valves which is or are opened as the power-piston arrives at the end of its stroke and is or are closed as the piston starts upon its return-stroke, a pump or pumps by which a partial vacuum is formed in the exhaust pipe or pipes before the exhaust valve or valves is or are opened, and a pump or pumps for compressing the charges into the power-cylinder in front of the advancing piston, substantially as described.

10. The combination, with the power-cylinder and the pump or pumps for compressing the charges into the cylinder, of the induction pipe or pipes 55 56 and valve or valves 41, and the check valve or valves 42, located between the induction valve or valves and the pump or pumps and opening toward the induction valve or valves, whereby a portion of the charge is entrapped in the induction-pipe under pressure and prevented from being drawn back into the pump upon its suction-stroke, substantially as described.

11. The combination, with the power-cylinder and the pump or pumps for compressing the charges into the cylinder, of the induction-pipes 55 56 and valves 41, the valves 42 between the induction-valves and the pump or pumps, and the pipe 54, connecting the induction-pipes between the valves 42 and the induction-valves, substantially as described.

12. The combination, with the power-cylinder and a pump for compressing the charges into the cylinder, of connections between the pump and cylinder by which the pump, after compressing the charge into one end of the cylinder during the last part of its stroke, forces a quantity of the explosive mixture into

the other end of the cylinder to aid in expelling the products of combustion, substantially as described.

13. The combination, with the power-cylinder and a pump for compressing the charges into the cylinder, said pump being arranged to complete its stroke after the power-piston has completed its stroke, of connections between the pump and power cylinder by which 10 the pump, after compressing the charge into one end of the power-cylinder during the last part of its stroke, forces a quantity of the explosive mixture into the other end of the cylinder to aid in expelling the products of combustion, substantially as described.

14. The combination, with the mixing-chamber 99 and the pump for withdrawing the mixture from the chamber, of one or more loosely-mounted mixing-wheels having oblique vanes, 20 whereby it or they is or are revolved by the current passing through the chamber, substantially as described.

15. The combination, with the mixing-chamber 99, of a plurality of mixing-wheels arranged to be revolved in different directions, 25 substantially as described.

16. The combination, with the annular chamber 94, having the openings 2 and the central opening, 14, of the valve 93, arranged to close 30 said openings, and the check-valve 95, substantially as described.

17. The combination, with a stationary igniting-burner located in a recess in the valve-chest, of a firing-valve having an explosion-chamber which is filled with an explosive 35 mixture and communicates with the power-cylinder through a check-valve, and which is provided with a port through which it is brought into communication with the igniting-burner by the movement of the valve at 40 the proper time to fire the charge, substantially as described.

18. The combination, with a firing-valve having an explosion-chamber which communicates 45 with the power-cylinder through a check-valve, of connections, as the channels 7 and port 9, through which the chamber is brought into direct communication with the power-cylinder to be filled from the mixture 50 therein as the valve is moved, substantially as described.

19. The combination, with a firing-valve having an explosion chamber which communicates with the power-cylinder through a 55 check-valve, of a pump, as 36, communicating with a gas-supply, and connections, as the duct 6, channel 1, and port 9, through which the chamber is brought into communication with the pump as the valve is moved, substantially 60 as described.

20. The combination, with a stationary igniting-burner, of connections, as the channel 3 and duct 4 5, by which the burner is fed

from the charge in the power-cylinder, substantially as described.

65

21. The combination, with a stationary igniting-burner fed by a mixture of gas and air and a stationary master-light, of a valve having a channel, as 18, by which the igniting-burner is brought into communication 70 with the master-light as the valve is moved, substantially as described.

22. The combination, with a stationary igniting-burner, of connections, as the channel 3 and duct 4 5, by which the burner is fed 75 from the charge in the power-cylinder, and a firing-valve by which the burner is brought into communication with the power-cylinder at the proper time to fire the charge, substantially as described.

80

23. The combination, with a stationary igniting-burner fed by a mixture of gas and air and a stationary master-light, of a valve by which the igniting-burner is brought into communication with the charge in the cylinder 85 to explode it, and by which the burner is also brought into communication with the master-light to be relighted after each explosion, substantially as described.

24. The combination, with a stationary igniting-burner, of a firing-valve having an explosion-chamber which is brought into communication with the igniting-burner through the oblique port 9, substantially as described.

90

25. The combination, with the plate 51, 95 forming the side of the valve-chest, and also the valve-seat, of the valve 30, arranged to be pressed to its seat by the charge in the power-cylinder, substantially as described.

26. The combination, with the cylinder or 100 cylinders 36, provided with suction and force valves, of the valve-rod 32, forming a plunger or plungers for said cylinder or cylinders, substantially as described.

27. The combination, with the firing valve 105 or valves 30, having the explosion chamber or chambers 22, of the cylinder or cylinders 36, communicating with said chamber or chambers, and the valve-rod 32, forming a plunger or plungers for said cylinder or cylinders, 110 substantially as described.

28. In a gas-engine, the combination, with the power cylinder, piston, and piston-rod, of the open trough 53, for containing a quantity of water to surround the rod and keep it properly cooled, and the two stuffing-boxes through 115 which the rod passes, substantially as described.

In testimony that I claim the foregoing I have hereunto set my hand this 12th day of 120 May, 1883.

PETER MURRAY, JR.
